ADDRESSING AND LISTING MACHINE

Harmon P. Elliott, Watertown, Mass.

Application April 10, 1935, Serial No. 15,593

34 Claims. (Cl. 101—47)

This invention relates to printing machines of the type wherein the data to be printed is carried by movable printing devices as stencils.

The invention has particular reference to printing or addressing machines having provision for printing lists and especially duplicate lists of a part only, as the name and certain other data carried by each, or selected ones, of the printing devices or stencils.

10 In the use of an addressing machine in an insurance office, for instance, each of the stencils or printing devices may contain the name of the policy holder with the amount of the policy in one line of the stencil and other data 15 on other lines of the stencils. At times it is desirable to compile lists of the names of selected ones of the policy holders and the amounts of the policies without at the same time printing the other data contained by the stencils; and an 20 object of the present invention is an improved form of machine for this purpose.

It is also desirable to print duplicate lists of the names of the policy holders and the amounts of the policies and a further object of the invention is an improved form of machine for this 25 purpose.

In accordance with this invention and as an object thereof the duplicate lists are secured to a movable holder and mechanism is provided for effecting two printing operations upon the same 30 stencil and for moving the holder to position the separate lists in succession in printing relation with the stationary stencil so that a separate list will be printed at each printing operation and then to advance both lists into position to receive on a succeeding line of the lists the data 35 of a succeeding stencil.

In the present machine, the list holder is advanced by a reciprocating link that makes one 40 complete cycle for each printing operation. The list, however, is intended to be advanced once for each two printing operations. Hence a further object of the invention is the provision of mechanism for so controlling the list advancing mechanism that the link is effective in advancing the 45 list at alternate cycles only.

The machine of the present invention is arranged to advance the stencils between every two printing operations, when the successive stencils 50 are such that the printing of the data carried thereby is desired. When, however, the data of a stencil is not desired to be recorded, it is desirable to pass that stencil and advance to the next stencil to be printed from as rapidly 55 as possible in order to save time. Hence a fur-

ther object of the invention is the provision of mechanism for effecting the advance through the printing position of stencils that are used for printing every other cycle of operation of the machine and for advancing unwanted stencils 5 every cycle of operation.

The printing machine embodying the present invention is provided with selector mechanism to determine which stencils of the collection shall be used for printing. It is common to operate the selector mechanism to feel a stencil at each printing operation. In the present instance, however, this method of operation will result in an improper operation of the machine and hence it is an object of the present invention to provide 10 mechanism that controls the selector mechanism in such manner that the selector mechanism is operated to feel a stencil but every other cycle, or 15 printing operation, of the machine.

Further objects of the invention reside in a novel construction of the list holder and in the 20 mechanism for advancing the holder.

A yet further object is generally to improve the construction and operation of printing and addressing machines.

the cam roller that control the advance of the sheet holder; Fig. 14 representing the position of the parts at the start of advance of the cam and movement of the cam roller toward the front of 5 the machine; Fig. 15 representing the advanced position of the parts; Fig. 16 representing the rearward or feeding movement of the cam roller, the cam being stationary; Fig. 17 representing the second advanced position of the cam and 10 roller from the position of Fig. 16, both moving conjointly without material relative movement therebetween, and Fig. 18 the rearward movement of the cam roller into the position of Fig. 14, the roller dropping off the high part of the stationary cam before moving into a position to 15 advance the lists.

Fig. 19 is a plan view of a list.

Fig. 20 is a plan view of a stencil.

The printing device used in connection with 20 the present invention comprises a stencil 22 having a window therein occupied by a stencil sheet 24 bearing lines of printing data of which one line 26 may have the name of the holder of an insurance policy and the amount of the policy, 25 and other lines 28 may contain various desirable data.

The machine of the present invention is intended to print the data of a certain part only 30 of the stencil, as the data of the line 26, in duplicate upon a list, such as the list 30 of Fig. 19, such list having a panel 32 therein to receive the various names of selected stencils and a series of lines 34 arranged in a vertical column in which the data of the lines 26 of the selected stencils 35 are arranged one under the other. In the present instant two such lists are placed side by side and the machine is arranged to present the selected data of a stencil in duplicate on both lists.

The stencil 22 is provided with one or more 40 selector perforations 36, or equivalent means, suitably positioned in the stencil, in accordance with well known practice, to permit the selection for printing of certain stencils only of a collection.

45 The machine embodying the present invention comprises a frame including a table or bed 38 supported on legs 40 and 42. A pair of stencil rails 44 are spaced above the top of the table and extend in horizontally spaced parallel relation over the table and constitute a track in which the successive stencils 22 are advanced from a vertical stack of stencils contained in a stencil holder 46 located above one end of the track and through a printing position and into 55 a stencil receiver 48 located at and depending below the track at the other end thereof.

The printing mechanism, see especially Figs. 1, 2 and 3, includes a vertically movable printing head 50 located above the stencil track and a 60 vertically movable anvil 52 located below the stencil track. The printing head is provided with an impression pad 54 having a raised or stencil engaging section 56, see also Fig. 13, that is adapted to engage only with the line 26 of the stencil so as to print the data carried by this line only, the remainder of the impression pad being free from contact with the stencil. The printing head 50 is carried by the forwardly extended ends of arms 58 that are carried by a 65 horizontal loop frame 60 disposed at the rear of the stencil track and pivoted on a shaft 62 carried by a bracket 64 secured to the under-side of the table 38. The raised portion or ledge 56 of the impression pad is supplied with ink by means of a 70 horizontally swinging inking roller 66 that re-

cipitates forwardly and rearwardly over the face of the impression pad and into and out of rolling contact with the lowermost one of a series of ink conveyor rolls 68 which receive ink from a distributing drum 70, see Fig. 1, that is supplied with ink from an ink reservoir 72.

The construction of the printing head and the inking mechanism therefor is described and claimed in my copending application Serial No. 5,944, filed February 11, 1935, and need not be 10 further described here.

The platen 52 is mounted between and is integral with the forward ends of arms 74 that are pivoted at 76 to the rear part of the bracket 64. The platen and the printing head are adapted 15 to be reciprocated toward and away from each other in timed relation so that the platen supports a work sheet beneath and in contact with the stencil at the time the printing head moves into pressure engagement with the stencil. 20

The operating mechanism for reciprocating the printing head and anvil includes a horizontal shaft 78 supported by the bracket 64 and providing pivotal support for an operating arm 80 which is reciprocated in a vertical direction. 25 Said arm is pivotally connected through a toggle link 82 with the lower end of an arm 84 depending from the loop frame 60 of the printing head so that the reciprocation of said arm 80 effects the reciprocation of the printing head. 30 The reciprocation of the arm 80 also effects the reciprocation of a generally vertically extended cam arm 86 having an upper cam face 88 that cooperates with a cam roller 90 carried by the platen for effecting the reciprocatory movements 35 of the platen.

The arm 86, see especially Fig. 4, has a latch 92 pivoted thereto which is normally biased to hold its latch projection 94 within a notch of an operating sector 96 that is pivoted on the shaft 40 78 so that the arm 80 and sector 96 normally reciprocate in unison. The engagement of the latch with the sector, however, is under control of the selector mechanism and is at times disengaged from the sector as will be explained later. 45 The sector 96 is reciprocated by means of a connecting rod 98 from a power plant 100, see Fig. 1, of well known construction having mechanism under control of a foot pedal 102 that effects one complete reciprocatory movement of the 50 connecting rod and hence one complete cycle of operation of the machine for each depression and immediate release of the pedal. When, however, the pedal is held down by the operative, as is the case with normal operation of the machine, 55 the machine will operate continuously.

The lists, such as the list 30 of Fig. 19, on which the data of selected stencils is adapted to be printed, is carried removably by a holder that is capable of step by step, or line by line, advance 60 toward the printing position and also is capable of reciprocatory movement in a transverse direction. The list holder, see Figs. 1, 2, 3, 4 and 12, includes a guide bar 104 that is secured to the table 38 of the machine in front of the printing head and projects forwardly at right angles to the stencil track. The bar is provided with a longitudinal T slot and forms a guideway for a slide bar 106 of the stencil holder, which slide bar is T shaped in cross section to fit the groove 70 of the guide bar. A plate 108 is secured at its median line to the top face of the slide bar and projects laterally in both directions therebeyond. A pair of undercut spaced parallel plates 110 are secured to the forward end of the slide 75

bar upon said plate 108 and form a guideway for a cross slide 112 which carries the lists. A strip 114, see especially Figs. 11 and 12, is secured to the cross slide and has its long forward edge 116 upturned, that is to say, the edge facing the front of the machine, both ends 118 of the strip are also upturned to form a pocket between which the lists are clamped. The left hand end of the slide is provided with upstanding ears 120 in which the rear end of a rod 122 is journaled. The rod 122 projects forwardly of the cross slide and parallel with the slide bar 106 and forms means for connecting the cross slide in any advanced position thereof with stationarily located reciprocating mechanism, as will be explained hereinafter.

A clamping bar 124 is fixed to the rod 122 between the ears 120 and overlies the cross slide on the strip 114 and has longitudinally spaced rubber clamping feet 126 on its under face. The bar is capable of being locked releasably in a clamping position by a hand operated lever 128 which is pivoted to the cross slide and has parts that overlie and press down upon the free end 25 of the clamping bar. The list holder is adapted to hold two lists at a time, as indicated in Fig. 11, the lists having their adjacent marginal portions overlapping so that the data-receiving panels 34 are side by side with the vertical lines thereof 30 in alignment and spaced laterally apart a suitable amount to cause the selected data of the stencils to be printed in the same relative position in each panel.

The list holder is adapted to be moved laterally under the printing head or in a direction lengthwise of the stencil track to position first one list and then the other list under the printing head so that both can receive by successive operations the same data of a stencil. After both 40 lists have received this data the list holder is advanced by the amount of one vertical line of the list so as to position both lists to receive the same data of the next desired stencil.

The mechanism for reciprocating the lists, and 45 hence the cross slide 112, comprises a vertically extended lever 130, see Figs. 1, 2 and 3. Said lever is pivoted on a shoulder screw 132 carried by a bracket 134 fixed to the leg 40 of the machine and extends in front of the forward edge 50 of the table 38 at the left hand side of the sheet holder and is adapted to be reciprocated laterally or in the direction of the stencil track. A link 136 is pivoted to the upper end of said lever and the other end of said link is loosely received slidably upon the forwardly extended rod 122 of the cross slide. The arrangement is such that said rod can move in said link while remaining operatively connected therewith so as to effect the reciprocation of the cross slide and 60 lists in any advanced position thereof.

The lever 130 is reciprocated in an intermittent manner by means including a double lobed cam 138 fixed to a drum 140, see especially Figs. 9 and 10, that is loose upon the forward end of a stud 65 shaft 142 carried by the aforesaid bracket 134. The drum 140 is engaged with a brake mechanism 144 which prevents unwarranted movement, or overthrow, of the drum and cam. The drum is also provided with peripherally outstanding 70 ratchet teeth 146 engaged by a pawl 148 pivotally carried at the end of an arm 150 of a hub 152 loosely journaled on the stud shaft 142 behind the drum, see also Fig. 10½. The hub 152 is provided with another arm 154 arranged in 75 a diametrical line with the pawl arm 150 and

pivotedly connected to the lower end of a link 156, the upper end of which is pivotally connected to a forwardly extended projection 158 that is rigid with and oscillates with the operating arm 80 of the printing mechanism so that the reciprocatory movements of the cross slide 112 and consequently the list 32 are controlled by and operate in timed relation with the operation of the printing mechanism. Thus when the printing mechanism is disabled the list reciprocating mechanism also is disabled. The shape of the double lobed cam 138 and the operation of the intermittent rotating mechanism for the cam is such that the cross slide 112 is moved alternately in opposite directions an amount 15 equal to the spacing between the panels 32 of the two lists between successive printing operations on the same stencil and is held stationary for a time in each of its opposite positions.

The list holder and the lists thereon are advanced rearwardly through the printing position in a step by step manner, one line at a time, between each two printing operations. The advancing mechanism, see Fig. 3, includes a link 160 which is located under and is extended parallel with the slide bar 106 of the list holder and has its rear end pivotally connected to the cam arm 80 that reciprocates the platen or anvil 52. Thus at each printing operation the link 160 is reciprocated forwardly and rearwardly. The front end of the link extends through a U-shaped guide 162 depending from the guide bar 104. The forward end of the link is provided with a horizontally elongated slot 164 and a latch block 166, see also Fig. 8, that is disposed against one face of the bar at the slot and has a pair of laterally extended pins 168 and 170 which are located in the slot on opposite sides of the guide yoke. A pair of tensile springs 172 are connected with the rear pins 170 and with eyes 174 carried by the guide bar 104 and tend to hold the latch block in such position that the pins 170 bear against the sides of the guide yoke 162. A latch 176 is pivoted on the forward pin 168 and extends upwardly and rearwardly above the block and 45 operates in a slot 178 in the bottom of the guide bar to engage rack teeth 180 formed in the bottom face of the slide bar 106 of the list holder. A compression spring 182 bears upon the latch in a direction to maintain it yieldingly in elevated 50 position and the latch has a limit member 184 that limits the upward movement of the latch due to said spring 182.

The arrangement is such that the operating link 160 can move rearwardly without advancing 55 the latch block 166 until the pin 168 is seated in the bottom of the slot 164 whereupon further movement of the link in the same direction causes the latch block and the latch to advance and thereby to advance the list holder if conditions are such that the latch is in engagement with a tooth of the slide bar 106.

Both the link 160 and the latch 176 are provided with forwardly extended fingers 186, 188, respectively, by which the latch can be moved 65 away from the slide bar so that the slide bar can be moved forwardly or rearwardly by hand to position it in any selected position with respect to the printing mechanism for the start of a list printing operation.

Since the link 160 by being connected with the arm 80 of the printing mechanism makes two complete reciprocatory movements during the dual printing operation on the same stencil and yet the list holder is required to be advanced 70 75

but once during this dual printing, mechanism is provided herewith for rendering every alternate reciprocatory movement of the list advancing link 160 ineffective in advancing the list holder. Said mechanism, see Figs. 1 and 3, includes a multi-lobed cam disc 190, a notched brake disc 192, and a multi-toothed ratchet disc 194 pinned or otherwise secured together in the order named and mounted rotatably upon a stud shaft fixed 10 to the depending bracket 198 carried by the table 38 under the list advancing link 160. A ratchet arm 198 on the stud shaft is mounted concentrically with the cam and ratchet discs and is connected to the link 160 by a pin 200 which pin 15 operates in a generally vertically positioned slot 202 of said arm. Thus said arm 198 is reciprocated concurrently with said link 160.

Said arm 198 is provided with a pawl 204 that engages the teeth of the ratchet disc 194 and thus 20 the ratchet and cam discs are caused intermittently to advance or rotate in a counterclockwise direction at each forward stroke of the link 160. A flat spring brake strip 206 is secured to and depends from the table 38 and has a reflexed 25 end which is adapted to enter successive notches of the notched brake disc 192, whereby to hold the set of discs releasably in any moved position thereof.

The link 160 is provided with a depending lug 30 208 which at its lower end carries a cam roller 210 that at all times rests in contact with the cam disc 190. The cam disc is provided with a plurality of lobes 212 and thus the link 160 is supported either in an elevated or in a lowered position 35 depending upon whether the roller 210 is upon the top part of a lobe or is in the valley between two lobes. When the roller 210 is on top of a lobe the forward end of the link 160 is in elevated position and hence the latch 176 thereof can be engaged with one of the teeth 180 of the slide bar 176 of the list holder to advance 40 the list. The front faces 214 of the lobes 212, that is those faces that are directed towards the front of the machine, are substantially rectilinear 45 so that when any face is under the roller 210, as illustrated in Fig. 3, the face 214 is substantially parallel with the link 160.

The operation of the mechanism is essentially as follows, see especially Figs. 3 and 14 through 50 18. At some given instant the cam roller 210 and cam 190 are in the relative positions illustrated in Fig. 14, the cam roller and its link 160 being in advanced or extreme rear position. The roller is upon a straight front face 214 of a lobe, 55 which face is generally parallel with the link 160 and hence the link is supported in a lowered position, free from engagement with the list holder. The link 160 now retracts or moves towards the front of the machine and the cam also moves in 60 the same direction until both are in the position of Fig. 15, the roller and cam maintaining their relative positions but the roller and link being somewhat elevated and the high part of the lobe 212 being in the path of rearward movement of the roller. The link 160 now moves rearwardly. 65 Since the cam is held stationary the roller climbs the cam lobe and hence the latch 176 of the link is elevated and caused to engage the list holder and advance it one line, the final advanced position of the link being such that the roller is on the tip of the lobe, as in Fig. 16. The link 160 now again moves toward the front of the machine, the cam also advancing and in such manner that the roller 210 stays on the tip of the lobe to the end of the stroke of link and cam, as 70

in Fig. 17. The latch 176 yields and drags over the teeth 180 of the list holder without moving the holder. The link 160 is then moved rearwardly while the cam is held stationary. During the initial part of such movement the roller 5 drops off the tip of the lobe into the position of Fig. 18 before the lost motion between the latch block 166 and link 160 has been taken up and hence the link is free to move further or into the dotted position of the roller or into the initial 10 position of Fig. 14 to begin a new cycle.

It is desired to compile the lists from the data carried by selected stencils only of the collection. Hence selector mechanism is employed to condition the printing mechanism to operate only upon 15 selected stencils and to effect the passage of unwanted stencils through the printing position without printing therefrom. Heretofore the selector mechanism has been operated to feel a stencil at every printing operation. With the 20 present machine, however, the feeling of a stencil at every printing operation would result in an improper operation of the machine. For instance, if a selected stencil was in printing position and the next adjacent stencil which is felt by the 25 selector happens to be one that is not desired to be printed therefrom the selector mechanism would operate to disable the printing mechanism following the first printing operation on the stencil that is in printing position and would effect 30 the movement of such stencil out of printing position. Thus only one of the desired two impressions from the same stencil would be made. Hence the selector mechanism is so arranged as to feel a stencil only during alternate cycles of 35 operation of the printing mechanism.

The selector mechanism, see Figs. 1, 2, 5, 6 and 7, includes a selector frame 216 horizontally disposed above the stencil track adjacent the printing head and movable vertically toward and away 40 from that stencil that is in the stencil track next to the one in printing position. Said frame has a vertical guide member 218 slidable in a guide-way 220 carried by a bracket 222. The selector frame 216 has a plurality of pin receiving holes 45 224 into selected ones of which resiliently mounted feeler pins 226 are adapted to be positioned, the position of the pins corresponding to the position of the selector perforations 36 of the stencil of Fig. 20. The arrangement is such that 50 if a pin can enter a selector perforation during the descending movement of the selector frame and electrically engage a stencil rail an electric circuit is completed which either conditions the printing mechanism for a printing operation upon 55 that stencil or disables the printing mechanism so that the stencil can pass through the printing position without being printed from, as may be desired. The vertical guide 218 of the stencil frame is provided with rack teeth 228 which mesh with a gear sector 230 fixed to a horizontal shaft 232 that is oscillated to effect the reciprocation of the stencil frame. The oscillation of said shaft is effected through an upstanding arm 234 that is fixed to the end of the shaft 60 and is connected through a link 236 with the end of an upstanding arm 238 fixed to the shaft 240 at one end thereof. Said shaft at the other end has an upstanding arm 242 which is connected through a link 244 with the arm 246 of a 65 shaft 248 located at the rear of the table 38 and oscillated by the operating sector 96, see especially Fig. 4. For this purpose the shaft 246 has an arm 250 fixed thereto and depending therefrom below the table 38 and at its lower end provided with a 70 75

cam roller 252 that engages the cam face 254 of the sector 96. The arrangement is such that on the latter portion of the upward movement of the sector the roller 252 passes along the inclined lower cam face 256 of the cam and hence the lever and the shaft 248 are moved in a counterclockwise direction under urge of a spring 258 connected to the arm 250. This movement of the shaft takes place during the latter part of the printing operation and effects the downward movement of the selector frame into stencil feeding position.

The completion of an electric circuit through a stencil energizes an electromagnet 260, see especially Fig. 5, located at the rear of the machine which magnet pulls down one end of a lever 262 that is pivoted intermediate its ends, and raises the other end thereof to effect the raising of a latch 264, see especially Fig. 4, loosely pivoted on the shaft 248. The latch 264 is in control of a lever 266 pivoted intermediate its ends at 268 and having a lower end 270 disposed in position to engage the roller 272 of the latch 92 that controls the connection between the operating sector 96 and the operating arm 80 of the printing mechanism. A tensile spring 273 is connected with said lever 266 to bias the lever 266 for movement in a clockwise direction. The upper end of the lever is provided with a pair of vertically spaced detents 276 and 278 and the latch 264 is provided with a reversible hook member 280 disposed between the detents and adapted in the position shown to engage the lower detent 276 and in the reversed position to engage the detent 278. In the position shown the arrangement is such that a printing operation is effected when a circuit is completed through a stencil. In the reverse position of the hook 280 the opposite is the case. Thus with the arrangement shown the lever 266 is normally engaged with the latch 264 and the lower end of the lever is held in engagement with the latch 92 so that the printing mechanism is normally disabled. When, however, a desired stencil comes into selecting position the latch 264 is disconnected from the lever 266 thereby to release the latch 92 and to connect the operating arm 80 and the sector 96 to effect a printing operation.

The lever 266 is restored into engagement with the latch 264 during a part of every printing operation by means of a cam block 282 carried by the operating sector 96 and engaging a roller 284 of the lever 266 to rotate said lever in a counterclockwise and resetting direction. Thus after every printing cycle the lever 266 is reset, with the mechanism so far explained, to disconnect the operating mechanism from the operating sector 96.

With this method of operation only one impression would be made of the same stencil. Hence mechanism is provided to modify the above described manner of operation in such a way that the operating arm 80 and sector 96 when once engaged stay engaged for two complete printing operations. Said mechanism, see Figs. 4 and 5, includes a cam disc 286, a brake or retaining drum 288 and a ratchet wheel 290, all pinned or otherwise secured together for conjoint rotation and rotatably mounted upon a stud shaft carried by a bracket 292 fixed to and extending from the rear of the table. The cam disc 286 is disposed beside and under the latch 264 and the latch has a depending projection 294 that rides upon the cam disc. The cam disc has a plurality of lobes 296 that successively engage and raise the latch 264. The

arrangement is such that when a lobe 296 is under the latch projection 294 the latch is supported in an elevated position and thus is disengaged from the tripping lever 266 for the latch 92. When the projection 294 is in the valley between two lobes the latch 264 is free to move downwardly and thereby to engage and lock the tripping lever 266 in a position where it holds the latch 92 disengaged from the operating sector 96.

The cam disc is rotated intermittently in a step by step manner, each step being one-half the distance between two consecutive lobes so that a lobe and then a valley are positioned successively under the projection 294 of the latch 264. With this arrangement the latch 264 is held in elevated position during every alternate printing cycle so that it can not engage the tripping lever 266 and hold it in a position to hold out the latch 92. Thus two printing operations are effected on any one stencil for one feeding operation thereof.

The cam disc 286 is held releasably in any advanced position by a resilient retaining strip 298, the reflexed end of which enters the successive notches of the brake disc 288. The cam disc is advanced in a step by step manner by an arm 300 pivoted concentrically with the cam disc and having a pawl 302 that engages the successive teeth of the ratchet disc 290. The arm 300 is reciprocated by means of a lever 304 connected with the operating arm 80 of the printing mechanism by means of a pin 306 carried by said arm and operating in a longitudinally extended slot 308 of the link 304. With this arrangement the arm 300 is moved during the upper and lower parts only of the stroke of the arm 80.

Since two printing operations are made upon the same stencil it follows that the selector frame 40 must be disabled during every alternate printing operation and that the stencil advancing mechanism must also be disabled for alternate printing operations. The mechanism for effecting these results will now be explained with reference to Figs. 1, 2, 6 and 7. The stencil advancing mechanism includes a pusher 310 which advances the successive lowermost stencils from the stack into and along the stencil track. The pusher is reciprocated by means of a connecting rod 312 which is located under the table 38 and is pivotally connected to the forwardly extended arm 314, see Fig. 2, of a bell crank having a vertical hub 316 pivoted to the table and having a right angularly related arm 318, the end of which operates in a cam slot 320, see Fig. 4, of the operating sector 96. The cam slot 320 is so shaped as to effect a complete reciprocation of the pusher for each complete reciprocation of the sector 96. The connection between the pusher and the connecting rod 312 is by means of a pin 322, see Fig. 7, connected with the pusher and operating in a longitudinally extended slot 324 of the connecting rod, which slot at the extreme end thereof has a lateral extension 326. When the pin 322 is in said extension the pusher and connecting rod are operatively connected for conjoint reciprocation. When, however, the link 312 is moved toward the left, Fig. 7, so as to position the pin 322 in line with the slot 324, the connecting rod is free for reciprocation without corresponding movement of the pusher.

The control of the connection between the connecting rod and the pusher is effected through cam mechanism generally similar to the cam

mechanisms heretofore described. Said cam mechanism includes a multi-lobed cam disc 328, a brake disc 330, and a ratchet disc 332 pinned or otherwise secured together for conjoint rotation in the order named, and fixed to a vertical shaft 334 journaled in a bracket 336 carried by the table 38 beside the connecting rod 312. A swinging arm 338 is pivoted on the bracket 336 and is located between the connecting rod 312 and the cam disc 328. Said link at its free end has on one side thereof a roller 340 that is engaged with the connecting rod and on its other side a roller 342 that is engaged with the cam disc 328. A tensile spring 344, see Fig. 2, serves to hold the connecting rod against the cam roller 340 and the cam roller 342 against the cam disc 328. The arrangement is such that when a depression or valley between two consecutive cam lobes 346 of the cam disc confronts the roller 342 the pusher 20 pin 322 is located in the lateral extension of the slot 324 of the connecting rod and the pusher is thus arranged for operation. So long as the valley between two lobes confronts the roller, the pusher is conditioned to advance a stencil for each stroke or cycle of the operating sector 96. When, however, a lobe of the cam disc confronts the roller 342 the link 312 will have been moved laterally to position the slot 324 of the connecting rod in line with the pin so that the pusher 30 and connecting rod will be disengaged and no stencils will be advanced, regardless of the number of strokes of the operating sector 96.

The advance of the cam disc is accomplished by the operating sector 96 but only as determined by the selector mechanism. The cam disc is advanced progressively in an intermittent manner by means including an arm 348 pivoted on the rotatable cam shaft 334 and having a pawl 350 engageable with the teeth of the ratchet disc 332. Said arm 348 is reciprocated through a connecting rod 352, see Figs. 2 and 7, pivotally connected to the forwardly extended arm 314 of the pusher operating bell crank lever. The free end of the rod is provided with a longitudinal slot 354 therein having at one end a lateral extension 355 in which slot and extension a pin 358 of the arm 348 can operate. A tensile spring 360 is connected with said connecting rod 352 and normally urges the connecting rod for lateral displacement into a position where the pin 358 is disposed in the slot 354 and thus the connecting rod and arm are operatively disengaged. When, however, the connecting rod is moved into the position indicated in Fig. 7 against the bias 55 of the spring 360 the pin 358 is disposed in the lateral extension 356 of the slot and thus the arm and connecting rod are operatively engaged to effect progressive advancement of the aforesaid cam disc.

The purpose of this arrangement is to speed up the operation of the machine when stencils are passed through printing position without being printed upon. The normal arrangement is such that when a stencil is to be printed from, the stencils are advanced every second cycle of the machine. When, however, the selector mechanism finds an unwanted stencil it is desirable to move that stencil through the printing position as rapidly as possible and hence the stencil advancing mechanism is conditioned to advance a stencil at each cycle of the machine until the selector mechanism finds another stencil to be used for printing whereupon the stencil advancing mechanism is again set to advance a stencil 75 every second cycle.

The mechanism by which this result is obtained and the connection between the connecting rod 352 and the arm 348 is controlled includes a link 362 having a roller 364 at its forward end which engages the forward long edge of the connecting rod 352. The rear end of said link is pivotally connected to an upstanding arm 366 of the shaft 268, see also Figs. 4 and 5, to which the tripping lever 266 is fixed. With this arrangement when the tripping lever 266 is in the position illustrated 10 in Fig. 4 and thus is in a position to effect a printing operation of the printing mechanism upon a selected stencil, the connecting rod 352 is held by the spring 276 of the tripping lever in engagement with the arm 348 and thus the 15 pusher is arranged to operate every other cycle of the machine. When, however, the tripping lever 266 is held in latched position by the latch 264, which is the normal position except when a stencil has been selected for printing, the connecting rod 352 is free for movement into a disengaged position with respect to the arm 348 and the pusher is thus conditioned to be operated every cycle of the machine, the disconnection position of the connecting rod 352 and arm 20 25 348 being such that the pusher controlling cam disc 328 is left in such position that one of the valleys between the lobes confronts the roll 342.

It has been previously stated that mechanism 30 is provided to prevent the selector from feeling a stencil except during alternate printing operations. The mechanism is further so arranged that it feels every stencil. Thus if there are a succession of unwanted stencils advanced along the stencil track and one stencil is advanced 35 every cycle of the machine the selector is arranged to feel each stencil and thus makes one operation for every cycle of the machine. When, however, the selector finds a stencil that is to be printed from, the selector is arranged to be disabled for the next cycle. The mechanism for accomplishing this result includes a cam disc 368 fixed to the aforesaid shaft 334 that carries the pusher controlling cam disc 322. Said cam disc 368 is located above the table 38 and has as many 40 lobes 370 as there are lobes on the cam disc 328, the lobes of both discs being in line. A link 371 is pivoted at its rear end to the upwardly extended arm 372 of the shaft 248 that reciprocates with the selector frame 216. The forward end 45 of said link has a cam roll 374 that confronts the cam disc 368 and is movable toward and away from said disc and into and out of engagement therewith. Said cam disc 368 and roll 374 control the descending or operative movement 50 of the selector frame, which movement is under urge of the spring 258, see Fig. 4, when the arm 250 fixed to the shaft 248 is freed for movement by the position assumed by the cam 254 of the operating sector 96. Thus when a lobe of the locking cam 368 confronts the roller 374 the selector frame is held from moving sufficiently 55 downward for a selector pin 226 thereof to engage a stencil. When, however, a valley between two lobes of said cam disc confront the roller 60 65 374 the selector frame is free to descend into operative feeling relation with a stencil. The locking cam 368 is rotatable with the pusher controlling cam 328 and is so arranged that the selector frame is free to feel a stencil at the same 70 time the pusher is conditioned to advance a stencil so that if the pusher is conditioned to advance a stencil at each cycle of operation of the machine, or complete reciprocation of the operating sector 96, the selector frame will be 75

operated to feed a stencil during each cycle but when the pusher is disabled the selector mechanism also will be disabled and thus will feed only once of each stencil selected for printing notwithstanding that two cycles of operation of the machine take place to effect the dual printing of the stencil.

While the machine has herein been described for making a dual impression of selected stencils it will be apparent to those skilled in the art that triple or more impressions can be provided by a proper arrangement and control of the various control cam discs without further showing.

I claim:

- 15 1. A printing machine comprising means to advance successive printing devices into a common printing position, means for printing repeatedly the same data of each stencil and of a plurality of printing devices on the same list, means for advancing a list intermittently through the printing position following the plural printing of the same data only, and means for shifting the list laterally following each printing operation.
- 20 2. A printing machine comprising printing mechanism, means for advancing successive printing devices to the action of said mechanism, means for operating said mechanism to print repeatedly the same data of a printing device and of a plurality of printing devices on the same list, means for intermittently advancing a list through said mechanism following repeated printing operations only, and means for shifting the list laterally following each printing operation.
- 25 3. A printing machine comprising means to advance successive printing devices into a printing position, means to obtain duplicate impressions of the same data of each desired printing device, and of a plurality of printing devices on the same list means to advance a list intermittently through the printing position following a succession of printing operations only, and means for moving the list sidewise following each printing operation.

- 30 4. A printing machine comprising means to advance successive printing devices into a printing position, means to effect plural printing operations of the same data of any desired printing device, means for advancing a list in a straight line intermittently through the printing position following the plural printing operations only, and means for reciprocating the list in a straight line normal to the line of advance of the list following each printing operation.
- 35 5. A printing device as in claim 4, the list being carried by a list holder and the described movements of the list being effected through said list holder.
- 40 6. A printing machine comprising printing mechanism, means for advancing a succession of printing devices to the action of said printing mechanism, means for operating said printing mechanism to effect plural printing operations of the same data of any desired printing device, a list holder arranged to present a list to the action of said printing mechanism, means for advancing said holder toward said printing mechanism following said plural printing operations, and means for reciprocating said holder in straight lines normal to the line of advance thereof following each printing operation.
- 45 7. A printing machine comprising printing mechanism, means for advancing a succession of printing devices to the action of said printing mechanism, a list holder arranged to present a list to the action of said mechanism, and means to advance said list holder intermittently towards said printing mechanism following plural printing operations only of said printing mechanism.

- 50 8. A printing machine comprising printing mechanism, means for advancing a succession of printing devices to the action of said printing mechanism, a list holder arranged to present a list to the action of said printing mechanism, means for advancing said holder toward said printing mechanism, means for reciprocating said holder crosswise of the line of advance thereof following each printing operation including a reciprocating lever, and means providing an operative connection between said lever and holder transmitting the reciprocatory movement of said lever to said holder in any position of advance thereof.
- 55 9. A printing machine comprising printing mechanism, means for advancing a succession of printing devices to the action of said printing mechanism, a list holder arranged to present a list to the action of said printing mechanism, means for advancing said holder toward said printing mechanism, means independent of said holder advancing means for reciprocating said holder crosswise of the line of advance thereof including a reciprocating lever, and means providing an operative connection between said lever and holder transmitting the reciprocatory movement of said lever to said holder in any position of advance thereof, said last named means including a sliding connection between said lever and holder.
- 60 10. A printing machine comprising printing mechanism, means for advancing a succession of printing devices to the action of said printing mechanism, a list holder arranged to present a list to the action of said printing mechanism, means for advancing said holder toward said printing mechanism, means independent of said holder advancing means for reciprocating said holder transversely of the line of advance thereof comprising a reciprocatory lever, a rod carried by said holder and located transversely of the line of reciprocation of said lever, and means providing a sliding connection between said lever and rod.
- 65 11. A printing machine comprising printing mechanism, means for advancing successive printing devices to the action of said mechanism, a list holder arranged to present a list to the action of said mechanism, and means to advance said list holder by a plurality of successive intermittent steps toward said printing mechanism following plural printing operations only of said printing mechanism.
- 70 12. A printing machine comprising printing mechanism, means to advance successive printing devices to the action of said mechanism, a list holder arranged to present a list to the action of said mechanism, and means to advance said list holder intermittently towards said printing mechanism including a reciprocating member operable concurrently with said printing mechanism.

to have printed thereon in a row selected data of a plurality of printing devices, means for advancing said holder in a step by step manner toward said printing mechanism following all of the printing operations only, means for reciprocating said holder crosswise of the line of advance thereof following each printing operation including a reciprocating lever, and means providing an operative connection between said lever and holder transmitting the reciprocatory movement of said lever to said holder in any position of advance thereof.

8. A printing machine comprising printing mechanism, means for advancing a succession of printing devices to the action of said printing mechanism, a list holder arranged to present a list to the action of said printing mechanism, means for advancing said holder toward said printing mechanism, means independent of said holder advancing means for reciprocating said holder crosswise of the line of advance thereof including a reciprocating lever, and means providing an operative connection between said lever and holder transmitting the reciprocatory movement of said lever to said holder in any position of advance thereof, said last named means including a sliding connection between said lever and holder.

9. A printing machine comprising printing mechanism, means for advancing a succession of printing devices to the action of said printing mechanism, a list holder arranged to present a list to the action of said printing mechanism, means for advancing said holder toward said printing mechanism, means independent of said holder advancing means for reciprocating said holder transversely of the line of advance thereof comprising a reciprocatory lever, a rod carried by said holder and located transversely of the line of reciprocation of said lever, and means providing a sliding connection between said lever and rod.

10. A printing machine comprising printing mechanism, means for advancing successive printing devices to the action of said printing mechanism, means responsive to selected printing devices for disabling said printing mechanism and effecting the passage of selected printing devices through said disabled printing mechanism, a list holder arranged to present a list to the action of said printing mechanism and to a plurality of said printing devices, means responsive to the dual operations only of said printing mechanism for advancing said list holder intermittently toward said printing mechanism, and means responsive to each operation of said printing mechanism for reciprocating said list holder transversely of its line of advance.

11. A printing machine comprising a printing mechanism, means for advancing successive printing devices to the action of said mechanism, a list holder arranged to present a list to the action of said mechanism, and means to advance said list holder by a plurality of successive intermittent steps toward said printing mechanism following plural printing operations only of said printing mechanism.

12. A printing machine comprising printing mechanism, means to advance successive printing devices to the action of said mechanism, a list holder arranged to present a list to the action of said mechanism, and means to advance said list holder intermittently towards said printing mechanism including a reciprocating member operable concurrently with said printing mechanism.

and having a disengageable operative connection with said list holder, and automatically operative means responsive to the operation of said printing mechanism to move said member into and out of operative connection with said list holder.

5 13. A printing machine comprising printing mechanism, means to advance successive printing devices to the action of said mechanism, a list holder arranged to present a list to the action of said mechanism, means to operate said printing mechanism to make dual impressions of the same data of desired printing devices on the list, and means to advance said list holder intermittently towards said printing mechanism including a reciprocating member having a disengageable operative connection with said list holder, and automatically operative means to move said member into and out of operative connection with said list holder, said last named means being responsive to the operation of said printing mechanism and arranged to connect said list holder and reciprocating member following dual operations only of said printing mechanism.

10 14. A printing machine comprising printing mechanism, means for advancing successive printing devices to the action of said mechanism, a list holder arranged to present a list to the action of said mechanism, means for intermittently advancing said list holder toward said mechanism including a reciprocating member having a disengageable operative connection with said list holder for advancing it, and multi-lobed cam means for moving said member toward and away from said list holder to control the operative connection between said member and list holder, and means for advancing said cam half the distance between said lobes for each operation of said printing mechanism.

15 15. A printing machine comprising printing mechanism, means for advancing successive printing devices to the action of said mechanism, a list holder arranged to present a list to the action of said mechanism, means for intermittently advancing said list holder toward said mechanism, means including a reciprocating member having a disengageable operative connection with said list holder for advancing it, multi-lobed cam means for moving said member toward and away from said list holder to control the operative connection between said member and list holder, and means for advancing said cam means intermittently less than the distance between lobes for each operation of said printing mechanism.

20 16. A printing device as in claim 15, said cam and said member at times moving in the same direction and said member at other times moving in the opposite direction while said cam is stationary, said cam being of such shape as to hold said member in operative connection with said holder during one movement of said member independently of said cam and for holding said member out of operative connection with said holder for another independent movement of said member.

25 17. A printing machine comprising a printing mechanism, means for advancing a succession of printing devices to the action of said printing mechanism, a list holder arranged to present a list to the action of said mechanism, means for advancing said list holder intermittently toward said mechanism including a reciprocating member having a disengageable pawl and ratchet connection with said holder, a multi-lobed cam for holding said member in operative connection with

said holder and also out of such operative connection, said cam having such shape that when it is in one position it supports said member for movement in a potential advancing position but out of advancing engagement with said holder and when said cam is in another position it holds said member in operative advancing connection with said holder, and means for advancing said cam in a step by step manner to effect the advance of said holder during certain only of the potential advancing movements of said member.

30 18. A printing machine comprising a printing mechanism, means for advancing successive printing devices to the action of said mechanism, a list holder arranged to present a list to the action of said mechanism, and means for advancing said list holder intermittently toward said mechanism following duplicate printing operations only of said mechanism including a member having a disengageable connection with said list holder, means for reciprocating said member for each printing operation of said mechanism, cam means for effecting the operative engagement of said member with said list holder during alternate reciprocations only of said member, and means for advancing said cam means intermittently for each printing operation of said mechanism.

35 19. A printing machine comprising printing mechanism, means for advancing successive printing devices to the action of said mechanism, selector mechanism for conditioning said printing mechanism to operate only upon selected printing devices, and means responsive to the operation of said selector mechanism to pass unwanted devices out of printing position more frequently than wanted devices.

40 20. A printing machine comprising printing mechanism, means for advancing successive printing devices to the action of said mechanism, means operative to effect the repeated printing operation of said mechanism on a selected device, selector mechanism for conditioning said printing mechanism for operation only upon wanted devices, and means responsive to the operation of said selector mechanism for passing unwanted devices out of the printing position more frequently than wanted devices.

45 21. A printing machine comprising printing mechanism, means for advancing successive printing devices to the action of said mechanism, repeatedly cyclically operating means for operating said printing mechanism normally once for each cycle of operation thereof, means controlling the operation of said device advancing mechanism by said operating means for effecting one cycle of operation of said advancing means for every other cycle of operation of said operating mechanism, and means responsive to selected printing devices for disabling said printing mechanism and for effecting an operating cycle of said advancing means for each cycle of operation of said operating means.

50 22. A printing machine comprising printing mechanism operative upon successive printing devices, means responsive to selected printing devices for effecting repeated operations of said mechanism upon a selected device, means for advancing successive printing devices to the action of said printing mechanism intermittently following repeated operations upon selected devices, and means for operating said advancing means more frequently for other than selected devices.

55 23. A printing machine comprising printing

mechanism, means for advancing a succession of printing devices to the action of said mechanism, means for advancing a list towards said printing device following plural printing mechanism 5 on a selected one of said printing devices, selector mechanism governed by said printing devices controlling the operation of said printing mechanism upon selected devices, and means controlled by said selector mechanism governing the operation 10 of said advancing means to advance unwanted devices through said printing mechanism more frequently than selected devices.

24. A printing machine comprising printing mechanism, means for advancing successive printing devices to the action of said mechanism, selector mechanism movable into and out of feeling position with each device, means controlled by said selector mechanism for conditioning said printing mechanism for dual printing operations 20 on a selected device, means for effecting but a single feeling operation of said selector mechanism upon any printing device, and means for operating said advancing means more frequently upon unselected than on selected printing devices.

25. A printing machine comprising printing mechanism, means for advancing successive printing devices to the action of said mechanism, selector mechanism movable into and out of feeling position with each device, means controlled by 30 said selector mechanism for conditioning said printing mechanism for dual printing operations on a selected device, means for effecting but one feeling operation of said selector mechanism for each series of printing operations of said printing 35 mechanism, and means for operating said advancing means more frequently upon unselected than upon selected printing devices.

26. A printing machine comprising printing mechanism, means for advancing successive printing devices to the action of said mechanism, selector mechanism movable into and out of feeling relation with each printing device, means governed by said selector mechanism for controlling said printing mechanism to make repeated 45 printing operations upon a selected printing device, means governed by said selector mechanism for advancing a list toward said printing mechanism following the series of printing operations only of said printing mechanism, and means for effecting but a single feeling operation of said selector mechanism on any one printing device.

27. A printing machine comprising printing mechanism, means for advancing successive printing devices to the action of said mechanism, selector mechanism movable into and out of feeling relation with said printing means, common control mechanism for said advancing means and said selector mechanism and means for disabling both said selector mechanism and said advancing 55 means conjointly.

28. A printing machine comprising printing mechanism, means for advancing successive printing devices to the action of said mechanism, selector mechanism movable into and out of feeling relation with said printing means, and means for disabling both said selector mechanism and said advancing means conjointly including conjointly operated cam members one controlling said advancing means and the other said selector mechanism, and means conjointly controlling the movement of said cam members.

29. A printing machine comprising printing mechanism, means for advancing successive printing devices to the action of said mechanism, selector mechanism movable into and out of feel-

ing relation with said printing devices, a reciprocating lever having a disengageable connection with said advancing means for operating it, a rotatable cam disc controlling said breakable connection, means including a breakable connection 5 between said cam disc and lever for advancing said cam disc intermittently, a second cam disc rotatable with said first disc, means governed by said second cam disc for controlling the movement of said selector mechanism toward the printing devices, and means governed by the reciprocatory movements of said lever for controlling said breakable connection.

30. A printing machine comprising printing mechanism having a reciprocating arm, a reciprocating operating member, a latch connection between said arm and operating member, a latch lever controlling said latch, means for advancing successive printing devices to the action of said printing mechanism, selector mechanism movable 20 into and out of feeling relation with said printing devices having means controlling the position of said latch lever, rotatable cam means controlling the operation of said advancing means and said selector mechanism, and means governed by said latch lever controlling the operation of said cam means.

31. A printing machine comprising printing mechanism, an operating member therefor, a latch controlling the operative connection between said operating member and printing mechanism, means for advancing successive printing devices to the action of said printing mechanism, selector mechanism for conditioning said printing mechanism for operation on selected devices only, means governed by said selector mechanism for controlling said latch lever, and means responsive to the movement of said operating member for also controlling said latch lever.

32. A printing machine comprising printing mechanism, an operating member therefor, a latch controlling the operative connection between said operating member and printing mechanism, means for advancing successive printing devices to the action of said printing mechanism, selector mechanism for conditioning said printing mechanism for operation on selected devices only, means governed by said selector mechanism for controlling said latch lever, and means responsive to the movement of said operating member for also controlling said latch lever, said latch means including mechanism operative to effect repeated printing operations upon a selected printing device.

33. A printing machine comprising printing mechanism, a reciprocating operating member for said mechanism, a latch connection between said operating member and printing device, a latch lever controlling said latch connection, counting mechanism responsive to movements of said operating member for effecting a predetermined positioning of said latch lever during a predetermined number of operations of said operating member, said counting mechanism comprising a latch for said latch lever, a rotatable multi-lobed cam for at times holding said lever latch out of engagement with said latch lever, and means responsive to movements of said operating member for advancing said cam in an intermittent manner.

34. A printing machine comprising printing mechanism, a reciprocating operating member for said printing mechanism, a latch connection between said operating member and print-

ing mechanism, a latch lever controlling said latch connection, a latch for holding said latch lever in a predetermined position, means for advancing successive printing devices to the action of said printing mechanism, selector mechanism responsive to selected printing devices for tripping said latch and freeing said latch lever for movement, means responsive to movements of

said operating member for moving said latch lever in a potential latching position with said latch, and counting mechanism responsive to movements of said operating member for holding said latch out of engagement with said latch lever for a predetermined number of operations of said operating member.

HARMON P. ELLIOTT.

DISCLAIMER

2,035,695.—*Harmon P. Elliott*, Watertown, Mass. ADDRESSING AND LISTING MA-
CHINE. Patent dated March 31, 1936. Disclaimer filed May 4, 1937, by
the patentee.

Hereby enters this disclaimer to claims 10, 11, 19, 20, 21, 22, 23, 24, 25, 26, 27,
30, 31, and 32 of said specification.

Also hereby disclaims the subject matter of claims 1 through 9 of said patent
insofar as these claims relate to printing from raised type characters but not other-
wise.

[Official Gazette May 25, 1937.]
